BLASTING FUSE SPITTER

Filed Nov. 30, 1925

Inventor:
Thomas Spears,

by *John A. Walton*,
Atty.

UNITED STATES PATENT OFFICE.

THOMAS SPEARS, OF BISBEE, ARIZONA.

BLASTING FUSE SPITTER.

Application filed November 30, 1925. Serial No. 72,221.

The present invention is a blasting fuse spitter for effecting the ignition of a plurality of fuses simultaneously for blasting purposes, and further consists of the 5 method employed in effecting this result, and the maintenance of the fuse in the spitter.

In mine blasting, it is the practice to run ordinary powder fuses to the holes or points 10 where the blasting charge has been deposited, there usually being a multiplicity of such charges distributed at spaced points or places for effecting the character blast desired; and it is now the general practice 15 to apply a torch or lamp to the end of each fuse independently one after the other. This practice is rather dangerous to the miner, as it is necessary for him to light all the fuses, before retiring to a place of safety. 20 The smoke from the first few fuses fills the working place necessitating him to feel around for remaining fuses or charges, which often detains him longer than he is aware, and the first lighted fuse explodes 25 before he gets to a safe place. Also, many times the lamps or torches are blown out by the spouting of the powder from the end of the fuse, leaving the miner without a light, and causing him to grope around in 30 the dark to a place of safety, or forcing him to attempt to relight the lamp before the blast occurs. The resultant accidents are said to be from premature explosions and the vast majority of blasting accidents 35 are thus occasioned.

It is the object of the present invention, therefore, to overcome the above stated drawbacks by the provision of a fuse spitter which is extremely economical, and 40 which is constructed to hold and retain the ends of the fuses in such a manner that all ends may be directly ignited by one flashing of a torch or lamp at the same time, the ends of the fuses being grouped together 45 and arranged in close relation, so that every lighting of one or any number of the grouped ends of the fuses will result in the ignition of the entire group.

A further object of the invention is in 50 the quick and simple method employed in grouping and retaining the ends of the fuses in a holding device or spitter.

With the above and other objects in view, the invention resides in the sundry details 55 of construction, combination and arrangement of parts, and in the steps of the

method employed hereinafter more fully described and set out in the appended claims.

In this specification and annexed drawings the invention is disclosed in the form in which it is considered to be the best, but the invention is not limited to such form and method, because it is capable of being embodied in other forms, and being performed in different manners; and it is to be understood that by and in the claims following the description herein, it is intended to cover the invention in whatever form it may be embodied, or in whatever manner it 70 may be practiced within the scope of said claims.

In the drawings which show the preferred embodiment of the invention as at present devised, and the manner in which the fuse 75 ends are held in the spitter:

Fig. 1 is a front elevation of the spitter constructed in accordance with the invention;

Fig. 2 is a front elevation of the spitter 80 showing the fuse ends attached thereto and the method by which they are held and retained in grouped relation in the spitter; and

Fig. 3 is a side view of the spitter shown 85 in Fig. 2.

Referring in detail to the drawings, the spitter of this invention consists of a panel or elongated stick of wood or other suitable material 10, which is slotted as indicated at 90 11. The slot 11 preferably extends from the upper end of the spitter for a desired distance inwardly thereof, although the slot may be arranged in any desired manner. The slot 11 is to be of such width as will permit the ends of the fuses to extend therethrough, and is preferably no wider than will accomplish this, so that the ends of the fuses may to an extent bind themselves in 100 the slot. The slot 11 may be of any desired length, but at least sufficient to accommodate the usual number of fuses which it is desired to ignite at one time.

While the spitter 10 is shown in the form 105 of an elongated panel with the slot extending from one end, leaving a handle portion 12 at the other end, so that the spitter may be conveniently held in one hand by the miner, this handle portion 12 may have its lower extremity pointed as at 13 in order that it may be stuck into the dirt, crevice, or other such place. The spitter 10 can be 110

made of any suitable material, and preferably from any waste strip of wood which is convenient and at hand, so that should the spitter become destroyed as a result of the blasting, the loss is very small.

The slot 11, as above stated, is adapted to have inserted therein a plurality of ends of fuses 14, the ends of the fuses being moved together in close relation, as illustrated in

- 10 Figures 2 and 3, preferably one above the other. The free extremities of the fuses which usually are of a corded construction are mashed or spread, as particularly shown in Fig. 2, so that these extremities will be 15 wider than the slot 11, and prevent the same from falling out. Also, this mashing or spreading of the ends of the fuses as at 15, causes the powder in said ends to be exposed, for convenient ignition. Since the 20 ends of the fuses 14 are in grouped juxtaposition in the slot 11, the ignition can be effected by merely applying a torch generally to the ends 15 of the fuses with the spitter. Of course, it is the practice for the 25 miner to run the torch along the ends of the fuses in order to use an abundance of precaution to insure the proper ignition of all of the fuses.

The ends 15 of the fuses, as above stated, 30 are mashed or spread to a size larger than the width of the slot 11, but this in some instances may be better effected by splitting the ends of the fuses with a knife or other implement.

35 It is also to be understood that it is within the purview of the present invention that the slot 11 be closed at both ends, but by having at least one end of the slot open it is found that the fuses may be inserted into the slot 40 from this end with greater facility and celerity.

From the foregoing, it will be seen that applicant has made a very simple and economical invention requiring no special and 45 expensive parts, and it maintains the fuse

ends in position as the same are merely disposed in the end of a slot, which is, preferably, of such size as to bind the ends therein; and by spreading the ends of the fuses in order to properly expose the powder therein for ignition, thereby requiring no supplemental or auxiliary detonator, or igniting charge to light the ends of the fuses.

What is claimed is:

1. A blasting fuse spitter comprising a 55 flat solid body member of substantial width and having a slot therein in which the ends of a plurality of fuses may be transversely extended with the ends of the fuses spread on a surface of the body member and grouped together for simultaneous ignition, said slot being of such width as to hold the fuses therein and said body member being of such width that the edges thereof project beyond the spread end of the fuses so when laid on one of its side edges it will support the ends of the fuses above supporting surface.

2. In combination, a unitary non-resilient fuse spitter comprising a solid body member having a slot extending for a distance thereinto from one edge thereof so as to provide an unslotted portion beyond the inner end of the slot, said slot being of a width to hold fuses transversely therein, the ignitable extremities of the fuses having bent over portions 70 adjacent to the edges of the slot.

3. In combination, a unitary non-resilient fuse spitter comprising a body member having a slot extending for a distance thereinto from one edge thereof so as to provide an 80 unslotted portion beyond the inner end of the slot, said slot being of a width to hold fuses transversely therein, said unslotted portion providing a handle having a penetrating end, the ignitable extremities of the 85 fuses having bent over portions adjacent to the edges of the slot.

In testimony whereof I have hereunto set my hand.

THOMAS SPEARS.
